UNITED STATES PATENT OFFICE

ANTHONY VANDERVELD, OF GRAND RAPIDS, MICHIGAN, ASSIGNOR TO GRAND RAPIDS STORE EQUIPMENT CORPORATION, OF GRAND RAPIDS, MICHIGAN, A CORPORATION OF MICHIGAN

METAL COUNTER CONSTRUCTION

Application filed September 17, 1930. Serial No. 482,454.

This invention relates to counters made of metal and is more particularly concerned with a novel, simple and very practical and durable counter construction made almost entirely from sheet metal. At the same time the construction is very economical to produce, may be quickly and easily fabricated and its parts quickly and easily assembled. It can be shipped in knock down form to limit the space required in shipment and assembled without the use of skilled labor when it reaches its destination and when assembled presents a very compact and pleasing appearance without projections extending therefrom.

An understanding of the invention for the attainment of the ends stated as well as many others not at this time enumerated may be had from the following description, taken in connection with the accompanying drawings, in which,

Fig. 1 is a perspective view of the counter made in accordance with my invention looking at the same at the rear thereof.

Fig. 2 is a longitudinal vertical section through the counter between its front and rear sides, looking toward the open rear side.

Fig. 3 is a vertical transverse section through the counter.

Fig. 4 is a fragmentary horizontal transverse section through one end portion of the counter.

Fig. 5 is a fragmentary longitudinal vertical section substantially on the plane of line 5—5 of Fig. 3.

Fig. 6 is a fragmentary enlarged vertical section substantially on the plane of line 6—6 of Fig. 2, looking in the direction indicated by the arrows.

Fig. 7 is a fragmentary horizontal section on the plane of line 7—7 of Fig. 6.

Fig. 8 is a fragmentary enlarged elevation of the lower part of the counter construction at the rear looking at the same in the same direction as in Fig. 2.

Fig. 9 is a horizontal section on the plane of line 9—9 of Fig. 8, and

Fig. 10 is a vertical section on the plane of line 10—10 of Fig. 9 looking in the direction indicated.

Like reference characters refer to like parts in the different figures of the drawings.

In the construction of the counter, a vertical front 1, and ends 2 are made from a single plate of sheet metal the ends being bent to lie at right angles to and extending rearwardly from the front. At both the upper and lower edges of the front and ends horizontal reinforcing flanges are turned inwardly, such as the lower flanges 3 and the upper flanges 3a. At the rear edges of each of the ends 2 of the counter, the metal is bent at right angles making a face section 4 which extends inwardly from its end 2 of the counter for a distance, is then bent back upon itself as indicated at 5, substantially one-half the width of the section 4, then turned again at right angles, as at 6, and then again bent back upon itself as at 7, whereby there is in effect provided a T-bar section at the rear edge of each of the ends 2 of the counter. This strengthens and reinforces the same materially and provides a means for connecting the lower securing and reinforcing members at the rear of the counter as will be hereafter described; also for the rear upper supporting and reinforcing members.

At the upper corners of the counter construction and extending longitudinally between the same are angle bars having vertical depending flanges 8 and horizontal flanges 9. The horizontal flanges at their ends are bent downwardly to provide ears 10. The angle bar support adjacent the front of the counter has its vertical flange 8 lying against the rear side of the front 1 and the ears 10 bear against the inner side of the ends 2. At the rear part of the counter there are two of the angle bar supports, one end ear 10 of each bearing against the inner sides of the sections 6 of the T-construction described, while the other ends thereof engage with a vertical T-bar which will be hereafter described as to its location and construction. Blocks 11 of metal lie against the inner sides of the ears 10 and against the outer sides of the parts against which said ears bear and screws 12 pass therethrough, threading into one of the blocks 11 (see Figs. 5 and 7), which serves

100

as a binding nut therefor, firmly securing the angle bar supports in place.

The upper sides of the horizontal flanges 9 of said angle bar supports are in the same plane with the upper edges of the front 1 and ends 2 of the counter. A sheet metal top is provided having a horizontal top section 13 at the edges of which are depending flanges 14 terminating in inwardly extending lips 15. The top is of sufficient size that it completely covers and extends beyond the front and ends of the counter and also the face sections 4 of the T-members at the rear, the in-turned lips 15 coming closely adjacent thereto. The top is detachably secured in place in any suitable manner the particular detail of which is no part of this invention and is therefore not shown or described.

At the rear open side of the counter a vertical post in the form of a T-bar, (previously noted), is located substantially midway between the two ends. This post has a rear face flange 16 and a forwardly extending tongue 17. It is against this tongue 17 that the adjacent ends of the two upper angle bars at the rear of the counter bear and through which the screw 12 passes. The blocks 11 which bear against the ears 10 at the ends of the angle bar supports are of a size to substantially cover the entire inner sides of said ears and are rigid so that there is no likelihood of the metal of the ears bending due to any strains put on the counter, as the blocks 11 bearing thereagainst hold the same snugly against the tongue 17 of the T-bar described and against the tongue sections 6 and 7 of the T-portions at the rear corners of the counter.

At the rear side of the counter and at its lower portion channel members of sheet metal are located between the central T-bar and the end T-sections described. There are two of these channel bars, each having a vertical web 18 and forwardly turned flanges 19. The flanges extend beyond the ends of the webs 18, each of said webs at its ends being formed with an inturned lip 20 to bear against the edges of the face flange 16 of the central T-bar, and against the bends between sections 4 and 5 where the same are bent back upon each other. This makes the outer sides of the webs 18 lie substantially flush with the outer sides of the sections 4 and the flange 16.

The flanges 19 of the channel members are each formed with an ear 21 turned at right angles to lie against the tongues 17 and the inner sides of the sections 6 described. Vertical bars 22 of metal extend between the upper and lower flanges 19 of the channel members at each end and cover the ears 21 thereof and screws 23 pass through said ears and through the tongues 17 and the sections 6 and 7, as shown in Fig. 9 to thereby securely connect the parts together and preclude any

bending or giving of the sheet metal tongues 21 under strains to which the counter may be subjected in use.

The counter construction described is, as is evident, open at its rear side and space underneath the top may be used to hold articles of merchandise on shelves 24, a plurality of which may be supported in the space. The way that the shelves are supported is no part of the present invention, the shelf supports being subject matter of a separate application for patent. The construction is one of a very practical nature. The parts are readily fabricated and easily assembled with the use of only a screw driver to drive the screws 12 and 23. The sheet metal parts may be made of relatively light gauge sheet metal but all sheet metal parts at all free edges thereof are strengthened and reinforced by inturned flanges and T-bar sections as disclosed.

The invention is defined in the appended claims and is to be considered comprehensive of all forms of structure coming within their scope.

I claim:

1. In a counter construction a vertical front and two spaced apart parallel vertical ends of sheet metal, horizontal supporting bars extending between said ends and having upper sides thereof in substantially the same plane with the upper edges and said front and ends, said bars being located between the rear portions of said ends and also closely adjacent the front, and elongated channel members located between said ends at their lower rear portions and connected thereto.

2. A counter construction comprising a vertical front and vertical ends located at right angles to the front and extending rearwardly therefrom, horizontal supporting bars located between said ends at their upper rear corners, a vertical post located midway between the said ends and between said supporting bars, said supporting bars being connected to the upper end of the post and to said ends of the counter construction, and channel members of sheet metal located between and connected to the lower end of said post and the lower corner portions of said ends of the counter.

3. A counter construction including, a vertical front and vertical ends of sheet metal, said ends being located at right angles to and extending rearwardly from the front, the rear edge portions of said ends being bent inwardly for a distance forming a face section then bent back upon itself a distance equal to substantially one-half the width of said face section, then bent forwardly at right angles for a distance then back upon itself whereby a vertical T-member is formed at the rear edge of each end of the counter, a vertical post located substantially midway between the said ends and at the rear portion of the counter,

angle bars extending between the upper ends of the post and the inwardly extending tongues of said T-member, channels between the lower ends of the posts and said T-members, and means for detachably securing the channels thereto, as specified.

4. A counter construction comprising a vertical front of sheet metal and integral vertical ends extending rearwardly therefrom and at right angles thereto, the rear vertical edges of each of said ends being bent inwardly then back upon itself, thence forwardly and then back upon itself, to provide vertical T-members having forwardly extending tongues, a vertical post of T-form having a forwardly extending tongue located at the rear portion of the counter between said ends, supporting bars extending between and connected at their ends to the tongues of said T-members at the upper ends thereof, and sheet metal channel members extending between and connected to the tongues of said T-members at their lower end portions.

5. A construction containing the elements in combination defined in claim 4, said upper supporting bars being of angle form each having a horizontal upper flange and a downwardly vertical extending flange and having an ear turned from one of said flanges at each end to lie against said tongues of the T-members, blocks of metal located against said ears, screws passing through said blocks and ears and tongues and nuts threading on to the ends of the screws, said blocks being of substantially the same area as said ears, for the purpose specified.

6. A construction containing the elements in combination defined in claim 4, each of said channels having a vertical rear web and forwardly extending horizontal flanges, said webs terminating short of the ends of said flanges and having forwardly turned lips bearing against the edges of the adjacent flanges of said T-members, ears turned vertically at right angles from the ends of said flanges of the channel members lying against the tongues of said T-members, vertical bars extending between and covering the ears at the ends of each channel member and also the outer sides of the tongues of the T-members formed on the ends of said counter, and screws passing through said tongues of the T-members, said ears, and one of said bars threading into openings in the other of said bars, as described.

7. A counter construction comprising a vertical front and ends made from a single plate of sheet metal, said ends being turned rearwardly at right angles to said front, horizontal supporting bars lying between said ends at spaced apart points and detachably connected thereto, a vertical post disposed at the rear portion of the counter construction substantially midway between the rear edge portions of said ends thereof to which

certain of said supporting bars are detachably connected, and lower bars between the lower ends of said posts and the lower rear corner portions of said ends of the counter detachably connected to said posts and ends of the counter.

In testimony whereof I affix my signature.
ANTHONY VANDERVELD.
